J. H. BRYANT

PLUNGER

Filed Feb. 27, 1925

John H. Bryant
INVENTOR
BY Victor J. Evans

ATTORNEY

UNITED STATES PATENT OFFICE.

JOHN H. BRYANT, OF CHICAGO, ILLINOIS.

PLUNGER.

Application filed February 27, 1925. Serial No. 12,146.

To all whom it may concern:

Be it known that I, JOHN H. BRYANT, a citizen of the United States, residing at 2621 N. Sawyer Ave., Chicago, in the county 5 of Cook and State of Illinois, have invented new and useful Improvements in Plungers, of which the following is a specification.

This invention relates to new and useful improvements in plungers and more particularly to that type which are generally used in washing machines. The main object of my invention is the provision of a novel type of plunger so constructed as to create a maximum amount of suction with 10 in the plunger when the same is being withdrawn from the cleansing fluid in which the clothes are contained so as to cause a thorough agitation of the fluid.

Another object of my invention is the 20 novel manner of mounting the piston or plunger within the cylinder to create an initial movement to said plunger or piston prior to the movement of the cylinder supporting the piston or plunger so as to create 25 a maximum amount of suction therein to thoroughly agitate the washing fluid.

With the above and other objects in view, my invention consists in the novel features 30 of construction and the combination and arrangement of parts to be hereinafter more fully described, pointed out in the claims and shown in the accompanying drawings, in which:

Fig. 1 is a side elevation of the plunger 35 constructed in accordance with my invention.

Fig. 2 is a vertical sectional view with the piston in its uppermost position.

Fig. 3 is a similar view with the piston 40 in its lowermost position.

Fig. 4 is a vertical sectional view through the entire device.

Fig. 5 is a transverse section on the line 5-5 of Fig. 2.

Referring now more particularly to the drawings the numeral 1 indicates the cylinder of my improved plunger having its upper end provided with internal screw threads 2, engaging with these screw threads is the 45 threaded flange 3 of the dome shaped cover 4. This cover 4 is provided at its top portion with an upstanding sleeve 5 forming a bearing through which the rod 6 reciprocates. The end of the rod which projects 50 into the cylinder 1 is provided with a reduced portion 7 adapted to be fitted into

the bearing 8 of the piston 9 and riveted as illustrated in Fig. 4, thus positively connecting the piston and rod.

Mounted within the plunger is a substantially conical shaped spring 10 the largest convolution of which is seated in an annular groove 11 formed in the side wall of the cylinder 1 at the inner end of the threads 60 2. Thus when the cover 4 is placed in position, the edge thereof which is threaded into the cylinder will abut the largest convolution of the spring 10 and retain the spring securely in position.

The spring 10 surrounds the rod 6 and has 70 positioned in its upper end a washer 12 which is retained against movement relative to the spring and rod 6 by means of a transverse pin 13 carried by the rod and normally engaging the upper face of the 75 washer. The washer 12 has a reduced portion 14 extending into the smallest convolutions of the spring 10 in order to retain the spring in its proper position relative to the rod.

The piston 9 is tightly fitted within the cylinder 1 for reciprocating movement and carries an extension ring 15 and is provided in its lower face with an arcuate cavity 16.

In the operation of my improved plunger 80 it will be apparent that on its downward movement, the cylinder 1 will pass through the washing fluid which is indicated at 17 and strike the clothes contained therein and further downward movement of the cylinder 90 1 is at this period prevented through contact with the clothes so that the continual movement of the rod 6 will overcome the tension of the spring 10, permitting the piston 9 to move to the outer end of the 95 cylinder as shown in Fig. 3, this movement reversing the position of the spring 10 and placing the same under considerable tension.

From the above it will be apparent that 100 upon the upper stroke of the rod 6 the piston 9 moves upwardly on its initial movement while the cylinder 1 remains stationary until the spring 10 again assumes its upright position as shown in Fig. 4. This initial movement relative to the cylinder 1 creates 105 a suction within the lower end of the cylinder, due to the cavity 16 in the lower face of the piston as is clearly illustrated in Fig. 4 so as to thoroughly agitate the washing fluid upon the various strokes of the 110 plunger.

It will be apparent from the foregoing

that I have provided a simple and inexpensive plunger for washing machines, the action of which creates a maximum amount of agitation in the washing fluid so as to 5 impart a greater agitation to the clothes through the fluid for cleansing the clothes. While I have set forth the fact that the device is particularly adapted for use in connection with washing machines, it will be 10 readily apparent that the same may be hand operated if so desired.

While I have shown and described the preferred form of my invention, it will be obvious that various changes in the details 15 of construction and in the proportions may be resorted to for successfully carrying my invention into practice without sacrificing any of the novel features or departing from the scope of the appended claims.

20 I wish to call attention to the fact that upon the initial upward stroke of the piston 9, a vacuum is created in the lower end of the cylinder 1 which causes the air and washing fluid to be sucked through the 25 clothes and upon the downward movement of the piston it will be noted that the air and water is forced through the clothes in the opposite direction, thus providing a thorough cleansing of the same.

30 Having thus described my invention, what I claim is:

1. A plunger including a cylinder having an annular groove therein adjacent one end, a piston mounted for movement in the cylinder, a rod having connection with the piston,

a conical shaped spring member having one end seated within the groove and encircling the rod, a stop pin carried by the rod and a washer between the stop pin and the other end of the spring. 40

2. A plunger including a cylinder having one end internally threaded and further provided with an annular groove at the inner end of the threaded portion, a cover member having threaded engagement with the cylinder, a piston in the cylinder, a piston rod movable through the cover and having connection with the piston, a spring member encircling the rod and having one end engaged within the groove beneath the inner end of the cover and means carried by the rod for bearing engagement with the other end of the spring. 45

50 3. A plunger including a cylinder having internal screw threads at one end and further provided with an annular groove at the inner end of the threaded portion, a conical shaped coil spring having its largest convolution seated in the groove, a cover threaded into the cylinder for engagement with the largest convolution to retain the spring in position relative to the cylinder, a piston movable in the cylinder, a rod connected to the piston and extending through the smallest convolutions of the spring and a washer 55 on the rod bearing against the latter convolutions. 60

65 In testimony whereof I affix my signature.

JOHN H. BRYANT.
